(57) **CLAIM**

The ornamental design for a display screen or portion thereof with a set of graphical user interfaces, as shown and described.

DESCRIPTION

The FIGURE is a front view of a display screen or portion thereof with a set of graphical user interfaces showing the claimed design.

The broken lines in the FIGURE show a display screen or portion thereof, and form no part of the claimed design.

The bracket shown in the FIGURE indicates a set. The set of graphical user interfaces is arranged relatively on the drawing sheet for the convenience of illustration, and the relative positioning forms no part of the claimed design.
